UNITED STATES PATENT OFFICE.

GEORGE J. ENGERT, OF SPOKANE, WASHINGTON.

MEANS FOR CONSTRUCTING HOLLOW CONCRETE WALLS.

Application filed February 6, 1922. Serial No. 534,605.

To all whom it may concern:

Be it known that I, GEORGE J. ENGERT, a citizen of the United States, residing at Spokane, in the county of Spokane and 5 State of Washington, have invented certain new and useful Improvements in Means for Constructing Hollow Concrete Walls, of which the following is a specification.

This invention relates to the construction 10 of hollow concrete walls and has for its object the provision of means whereby such a wall may be constructed expeditiously and inexpensively, the finished structure possessing all the necessary strength. The invention 15 contemplates the provision of a wall which will possess the strength of a solid wall and will contain an air chamber which may be a dead-air chamber to avoid the presence of moisture and transmission of 20 sound or may provide circulation through the entire height of the wall to permit foul air to escape through it beneath the roof of the building. The invention is illustrated in the accompanying drawings and 25 resides in certain novel features which will be hereinafter first fully described and then more particularly pointed out in the appended claims.

In the drawings—

30 Figure 1 is a perspective view showing a partly completed wall with my appliances in operative position;

Fig. 2 is a detail perspective view of the core or form whereby the air chamber is 35 produced in the wall;

Fig. 3 is an enlarged plan view of a supporting and reinforcing plate which is employed in the construction of the wall and which is embodied in the finished structure;

40 Fig. 4 is a detail perspective view of a fastening which is employed in the practice of my invention.

In constructing a wall according to my invention, I employ inner and outer falsework 45 or forms 1 which, as shown, consist of studding 2 and planks or boards secured to the studding so as to present a trough or hollow space between their opposed faces, the height of the falsework being increased as 50 the work progresses. At intervals corresponding to the courses of the wall, tension wires 3 are secured around the studding and extend through the planks or boards and are connected between the 55 boards, as indicated at 4, these tension wires serving to prevent outward collapse or spreading of the falsework. The foundation of the building may be a solid structure or may be hollow, as preferred, and the falsework will, of course, rise from the 60 foundation at the opposite sides of the same. Vertical reinforcing rods 5 are embedded in the foundation and rise therefrom at suitable intervals to extend to the height to which it is desired to carry the wall. The 65 upper surface of the foundation will, of course, be finished so as to be perfectly level and upon this level upper surface, I place a base plate 6 which will be of sufficient width to have its edges rest upon the foundation at opposite sides of the longitudinal 70 center thereof and between the reinforcing rods 5. Along the side edges of this base plate 6, I provide openings 7 in which are secured tie wires 8 which are wrapped about 75 and secured to the vertical reinforcing rods so as to hold the base plate firmly in position. Substantially U-shaped slits are formed in the base plate, thereby producing tongues 9 which may be struck up from 80 the slits, as shown clearly in Fig. 1, the spaces originally occupied by the several tongues producing openings 10 through which air may circulate in the completed 85 wall. The base plate having been secured in position, the form or core 11 is placed upon the base plate so as to rest thereon between the upstanding tongues and be held in position upon the plate by said tongues. This core or form is preferably a metallic 90 plate substantially U-shaped in cross section having its base 12 of sufficient width to rest upon the base plate snugly between opposed tongues 9 and having its sides 13 extending to any convenient height, ordinarily about eighteen inches. The form is 95 preferably constructed of resilient metal tempered so that the side members 13 thereof tend to spring toward each other at their upper edges. After the form has been placed upon the base plate 6, spreaders 14 are inserted between the sides of the form so as to maintain them in a spread-apart 100 position and reinforce them so that they will effectively resist the pressure of 105 the concrete exerted against them. These spreaders may be provided in any desired number at intervals along the length of the form or they may be co-extensive with the form so as to completely fill the same. As 110 shown in Fig. 2, they may be of less height than the form thereby leaving the upper

edges of the form free to be compressed and receive the cover in the event that the spreaders may be badly swollen from the effects of the water used in mixing the concrete. After the spreaders are properly placed, a cap or cover 15 is fitted over the top of the form, and this cap consists of an imperforate plate co-extensive with the form and having depending flanges 16 at 10 its side edges which engage the outer faces of the side members 13 of the form. Obviously, the cap or cover 15 prevents the entrance of the poured concrete into the form so that all of the concrete will be deposited 15 at the sides of the form and between the same and the falsework. The upper surface of the cap is smooth so that any concrete which may fall thereon may be readily scraped off and deposited in the space between the cap and the falsework. I also provide a holder consisting of a cross bar 17 which is equal in length to the distance between the opposed planks or boards of the outer forms or falsework, this holder being 20 provided near its ends with openings 18 through which the vertical reinforcing rods 5 may pass. The ends of the bar 17 are turned up, as shown at 19, and are T-shaped so as to provide a somewhat extended bearing against the falsework, openings 20 being formed through the heads of the upturned T-shaped ends to permit nails or similar fastenings to be driven therethrough into the falsework. On the underside of the 25 bar 17, midway the ends thereof, is a bracket or spaced depending lugs 21 which are adapted to engage the outer surfaces of the flanges 16 and thereby prevent lateral displacement of the cap 15 and the form. It 30 will be readily understood that the bar 17 is mounted slidably upon the vertical reinforcing rods 5 and is moved downwardly on said rods so that it will bear firmly upon the cap 15, as clearly shown in Fig. 1.

40 45 The several parts having been secured in position as described, green concrete is poured into the space between the opposed sides of the falsework and directed into the spaces between said falsework and the respective sides of the form, the pouring being continued until the level of the poured concrete reaches the edges of the cap. The concrete is then permitted to partly set and when it has set sufficiently to permit movement of the form, the fastenings by which the T-shaped ends of the holder are secured to the falsework are withdrawn and the holder is slid upwardly upon the vertical reinforcing rods. The cap 15 is then removed, 50 after which the spreaders 14 are withdrawn from the form 11. As the spreaders are withdrawn, the side members of the form will spring toward each other and free themselves from the partly set concrete, 55 whereupon the form may be lifted to a

point above the partly finished wall. A second base plate 6 is then placed in position over the partly finished wall and the described operation is repeated until the wall has reached the desired height, each successive base plate 6 being left embedded in the wall and constituting a reinforcement therefor. After the wall is finished, the falsework is, of course, removed and the projecting ends of the tension wires 3 are 70 cut-off flush with the surfaces of the wall. At proper intervals, removable cores may be placed in position in openings provided therefor in the falsework so that sockets to receive joists, indicated at 22, will be produced and in the same manner openings may be formed through the inner member of the wall to establish communication between the chamber of the wall and the spaces between the ceilings and floors of the building 75 so as to permit foul air from the rooms to escape. The described operation may be carried to the extreme top of the wall so that the opening produced by the use of the form 11 will terminate immediately at the 80 roof, but the extreme upper end of the wall may be formed solid, if preferred, and the last placed base plate 6 may have openings formed therein to communicate with pipes or tubes rising from the base plate through 85 the roof of the building.

It will be readily understood from the foregoing description, taken in connection with the accompanying drawings, that I have devised means whereby a hollow concrete wall may be rapidly produced and a strong structure obtained at a low cost. The forms and the other parts may be provided in standard lengths and when a number of them are required to provide for the desired length of a wall, the ends of the base plates may overlap and the ends of the forms may be telescoped so that a continuous outer surface will be presented for the proper forming of the poured concrete. Moreover, the overlapping or telescoping may be made deeper or shallower as circumstances may require so that door and window openings may be very readily formed in the wall as the same is finished. The base plates 100 may be shipped with the tongues 9 in a flat condition so that a large number of the plates may be piled one upon another within a relatively small space, thus facilitating transportation and reducing storage demands. In like manner, the several forms may be nested for transportation and storage so that the several parts may be easily transported from one point of use to another point of use.

Having thus described the invention, what is claimed as new is:

1. Means for forming hollow concrete walls comprising base plates adapted to be embedded in the wall, hollow open-top 130

- forms adapted to rest upon the said base plates, covers for said forms, and means extending across the covers for holding the covers and the forms in place.
- 5 2. Means for forming a hollow concrete wall comprising a base plate adapted to be embedded in the wall, a form resting upon the base plate and having resilient sides tending normally to approach, means on the 10 base plate for preventing lateral movement of the form, spreaders adapted to fit within the form, and means acting upon the top of the form to cover the same and to hold it to the base plate.
- 15 3. Means for forming hollow concrete walls comprising a base plate adapted to be embedded in the wall, a form adapted to rest upon the base plate and having resilient sides tending normally to approach each 20 other, spreaders adapted to be inserted within the form to maintain the sides thereof in a spread condition, a cover for the form, and a holder adapted to bear upon said cover and be fixed upon the same.
- 25 4. In the construction of hollow concrete walls, the combination of falsework between which the wall is to be produced, vertical reinforcing rods disposed within the space between the members of the falsework, base 30 plates to be embedded in the wall, means for securing said plates to the vertical reinforcing rods, forms adapted to rest upon the base plates, means for preventing lateral displacement of the forms, covers for the 35 forms, and holding bars slidably engaged upon the vertical reinforcing rods and bearing upon the covers for the forms and hav-
- ing their ends detachably secured to the falsework.
5. In the construction of hollow concrete 40 walls, the combination of outer forms, vertical reinforcing rods erected between said forms, base plates to be embedded in the wall, means for connecting said base plates to the vertical reinforcing rods, forms 45 adapted to rest upon the base plates between the reinforcing rods, means for preventing lateral displacement of the forms, covers for the forms, and holding bars slidably engaged upon the vertical reinforcing 50 rods and provided on their under sides with depending lugs engaging the edges of the covers, the ends of said holding bars being upturned and adapted to be detachably secured to the outer forms. 55
6. Means for forming hollow concrete walls comprising base plates to be embedded in the wall, forms adapted to rest upon the base plates and having resilient sides tending normally to approach, and means for holding the forms in place. 60
7. In the construction of hollow concrete walls, the combination of outer forms, vertical reinforcing rods erected between said forms, base plates to be embedded in the 65 wall, forms to rest upon the base plates between the reinforcing rods, and holding bars slidably mounted on the reinforcing rods and provided on their under sides with spaced projections to engage the inner 70 forms, the ends of said bars being detachably secured to the outer forms.

In testimony whereof I affix my signature.
GEORGE J. ENGERT. [L. S.]
